Specification for Design.

Patented May 25, 1920.

Application filed December 1, 1919. Serial No. 341,816. Term of patent 7 years.

To all whom it may concern:

Be it known that I, LOUIS J. RIPICH, a citizen of the United States, and resident of Cleveland, county of Cuyahoga, and State of Ohio, have invented a new, original, and ornamental Design for a Combination Lamp-Stand, of which the following is a specification, reference being had to the accompanying drawing, forming part thereof.

In said annexed drawing:—

I claim:—

The ornamental design for a combination lamp stand, as shown.

Signed by me, this 25th day of November, 1919.

LOUIS J. RIPICH.
